UNITED STATES PATENT OFFICE.

ORRELL ASHTON, OF LAWRENCE, MASSACHUSETTS, ASSIGNOR TO UNITED SHOE MACHINERY COMPANY, OF PATERSON, NEW JERSEY, A CORPORATION OF NEW JERSEY.

VAMP-TRIMMING MACHINE.

961,200.

Specification of Letters Patent. Patented June 14, 1910.

Application filed March 20, 1907. Serial No. 363,495.

To all whom it may concern:

Be it known that I, ORRELL ASHTON, a citizen of the United States, residing at Lawrence, in the county of Essex and State 5 of Massachusetts, have invented certain new and useful Improvements in Vamp-Trimming Machines; and I do hereby declare the following to be a full, clear, and exact description of the invention, such as will enable others skilled in the art to which it app- 10 pertains to make and use the same.

The present invention relates to machines which are used in the manufacture of shoes, and more particularly in the manufacture of 15 welted shoes, to trim off the projecting edges of the vamp and lining after the shoe has been lasted in order to prepare the shoe for the operation of the inseam sewing machine.

Certain features of the present invention 20 are also applicable to vamp trimming machines of that class which act upon the shoe after the inseam is sewn and which are known in the art as inseam trimming machines, as will be obvious to those skilled in 25 the art.

The object of the present invention is to provide a machine of the class above referred to having improved means for guiding the vamp and lining to the vamp trimming knife or knives and for causing the 30 vamp and lining to be properly presented to the knife or knives so as to be trimmed in a satisfactory manner at all portions of the shoe.

With the above object in view a feature of 35 the present invention contemplates the provision, in a vamp trimming machine, of a guide roll for the vamp and lining, arranged to engage the vamp and lining close 40 to the point of operation of the trimming knife or knives and to hold the vamp and lining in proper position as the shoe is fed past the knife or knives. To avoid any dragging action of the roll on the lining and 45 to assist the operator in feeding the shoe, the guiding roll is preferably rotated in a direction to cause the surface of the roll in contact with the lining to move in the direction of feed. In the preferred form of the 50 present invention the guide roll is used in connection with a fixed vamp trimming knife arranged to extend inside of the vamp and lining, and the roll is arranged to act upon the vamp and lining just in advance 55 of the cutting edge of the fixed knife. It is

desired that the guiding roll be located as closely as possible to the point at which the trimming knives act on the vamp and lining in order to properly support the vamp and lining and to bring the roll and knives into 60 as small a space as possible so as to permit narrow-toed shoes to be operated upon. To secure these results the roll is preferably arranged so as to overlap the blade of the trimming knife which extends inside of the 65 vamp and lining. In the preferred form of the invention hereinafter specifically described, two guiding rolls are provided, mounted in axial alinement with each other so as to constitute in effect a single roll, one 70 roll being located below and the other above the blade of the trimming knife which extends inside of the vamp and lining of the shoe. By the provision of these two rolls located above and below the blade of the 75 trimming knife a sufficient extent of surface in engagement with the vamp and lining is secured to guide the vamp and lining accurately to the trimming knives and support them properly during the trimming op- 80 eration.

The machine hereinafter specifically described as embodying the various features of the present invention is provided with a vibrating trimming knife which coöperates 85 with the fixed trimming knife and which moves in a direction transverse to the direction of feed. In accordance with a feature of the present invention, a vamp bending device is mounted to move with this vibrat- 90 ing trimming knife and is arranged to engage the vamp at each forward stroke of the knife and bend it inwardly toward the medial line of the shoe, so that any liability of the vamp and lining passing beneath the 95 vibrating trimming knife, is avoided. This vamp bending device extends at one side of the trimming knife and also preferably extends below the plane in which the trimming knife cuts, so that in addition to bending 100 the vamp inwardly it also serves to press the vamp closely against the shoulder at the edge of the insole.

In addition to the features of invention above referred to, the machine hereinafter 105 described embodies certain novel features of construction hereinafter described and claimed, the advantages of which will be obvious to those skilled in the art.

Referring now to the drawing accompany- 110

ing this application, Figure 1 is a view in side elevation of a vamp-trimming machine embodying the features of the present invention in their preferred form; Fig. 2 is a view in front elevation of the machine illustrated in Fig. 1; and Fig. 3 is a detail sectional plan view taken on lines 3—3 of Fig. 1.

The vamp-trimming knives of the machine illustrated in the drawing consist of a fixed vamp-trimming blade 1 and a vibrating trimming-blade 2, said blades being arranged in a horizontal plane and being provided with inclined cutting edges as illustrated in Fig. 3, so that the space between the cutting edges, when the blade 2 is at the limit of its backward movement, is V-shaped. The blade 1 is secured to or formed integral with the lower end of a shank or bar 3 which is secured to the overhanging head of the machine frame by means of bolts 4. The vibrating trimming-blade 2 is secured upon the forward end of a slide 5, mounted in horizontal guide-ways in the machine frame and actuated by an eccentric and strap from the driving shaft 6. The shaft 6 is mounted in the rear portion of the machine frame and is provided with fast-and-loose belt pulleys 7 and 8 and with a hand-wheel 9. The trimming blade 1 is adapted to extend inside of the vamp and lining of the lasted shoe over the insole, and the trimming blade 2 reciprocates toward and from the fixed blade transversely to the direction of feed, and cooperates with the fixed blade to trim the projecting edges of the vamp and lining as the shoe is fed past the knives.

In the machine illustrated in the drawing the vamp and lining are raised from the sole and directed between the cutting edges of the trimming knives by means of a guiding roll 10 which is secured upon the lower end of a vertical shaft 11. This roll is located below the plane of the blade of the fixed trimming knife and in order to bring the roll as closely as possible to the point at which the trimming knives act on the vamp and lining, the roll overlaps the cutting blade, the shaft 11 passing down through a hole in the end of the blade. The roll 10, as illustrated in Fig. 1, is frusto-conical in shape, and has its base of smaller diameter directed downwardly toward the sole of a shoe placed in the machine. This arrangement of the roll is preferable when narrow-toed shoes are operated upon, since the small end of the roll occupies less space in the shoe. In operating upon other styles of shoes, however, it is preferable to place the roll 10 in the machine so that its base of larger diameter is directed downwardly. The roll is accordingly so constructed that it can be placed in the machine in either position. To secure the roll upon the lower end of the shaft 11, it is provided with a

central bore extending completely through the roll, which bore is screw-threaded to engage a corresponding screw-thread upon the lower end of the shaft. The roll 10 can be relied upon alone to raise the vamp and lining from the sole and direct them between the cutting edges of the trimming knives. To provide a more extended guiding surface, however, the roll 12 is preferably provided, as illustrated in the drawing, which roll is screw-threaded upon the shaft 11, above the blade of the fixed trimming knife.

The means for rotating the rolls 10 and 12 to prevent drag on the lining and to assist the operator in feeding the shoe, consists of a worm gear 13 secured to the shaft 11, a shaft 14 journaled in the frame of the machine at right angles to the shaft 11, a worm on this shaft meshing with the worm gear 13, and a belt 15 passing over pulleys secured to the shafts 14 and 6. To render the action of the rolls on the lining more positive, the peripheral surface of the rolls is preferably knurled. The rolls are preferably rotated at a peripheral speed somewhat in excess of the speed at which the shoe is fed so that the rolls exert a pulling action on the lining and act to positively straighten out the lining and raise it from the sole. The roll 10 in addition to acting as a guide for the vamp and lining also acts as a gage to bear against the sole of a shoe and determine the position of the shoe with relation to the vamp trimming knives.

The vamp bending device is indicated at 16 and consists of a plate secured to the slide 5 by the same bolt 17 which secures the trimming knife 2 to the slide. The bolt 17 passes through a slot in the vamp bending device so that the device can be adjusted to the position in which it will act in the most satisfactory manner upon the particular style of work which is being operated upon. The work engaging surface of the vamp bending device extends across the upper surface of the blade of the vibrating trimming knife as illustrated in Fig. 3, and the bending device projects beyond the blade of the knife at one side and below the knife as indicated in Figs. 2 and 3 so that the device engages the vamp in advance of the cutting edges of the knife and also can act to press the vamp into the shoulder at the edge of the insole. The projection of the vamp bending device below the plane of the trimming knife 2 also acts effectively to prevent a fold in the vamp from passing beneath the knife.

The operation of the machine illustrated in the drawing has been indicated in connection with the description above given of the construction and arrangement of its various parts and will be readily understood by those skilled in the art without a separate description thereof.

The nature and scope of the present in-

vention having been indicated and a machine embodying the various features thereof in their preferred form having been specifically described, what is claimed is:—

- 5 1. A vamp trimming machine, having, in combination, vamp trimming means arranged to trim the projecting edges of the vamp and lining of a lasted shoe, and a guiding roll located in close proximity to the trimming means and arranged to extend inside of the vamp and lining of a lasted shoe and direct the vamp and lining to the trimming means.
- 10 2. A vamp trimming machine having, in combination, vamp trimming means arranged to trim the projecting edges of the vamp and lining of a lasted shoe, a guide roll to direct the vamp and lining to the trimming means and means for rotating the roll.
- 15 3. A vamp trimming machine having, in combination vamp trimming means, a frustoconical guide roll to direct the vamp and lining of a lasted shoe to the trimming means and means for securing the roll in the machine with either its base of larger diameter or its base of smaller diameter directed toward the sole of a shoe placed in the machine.
- 20 4. A vamp trimming machine having, in combination, a fixed vamp trimming knife arranged to extend inside of the vamp of a lasted shoe, a knife coöperating therewith to trim the projecting edges of the vamp and lining of a lasted shoe, and a guiding roll for the vamp and lining located beneath the fixed trimming knife.
- 25 5. A vamp trimming machine having, in combination, a fixed trimming knife arranged to extend inside of the vamp of a lasted shoe, a knife coöperating therewith to trim the projecting edges of the vamp

and lining of the shoe, and guide rolls for the vamp and lining located respectively above and below the fixed knife.

45

6. A vamp trimming machine having, in combination, a trimming knife arranged to extend inside of the vamp of a lasted shoe, a vibrating trimming knife coöperating therewith to trim the projecting edges of the vamp and lining of the shoe and a vamp bending device mounted to move with the vibrating knife and arranged to engage the vamp at each forward movement of the vibrating trimming knife.

55

7. A vamp trimming machine having, in combination, a trimming knife arranged to extend inside of the vamp of a lasted shoe, a vibrating trimming knife coöperating therewith to trim the projecting edges of the vamp and lining of the shoe and a vibrating vamp bending device mounted to move with the vibrating knife and extending at one side of the vibrating knife and below the plane of the knife arranged to engage the vamp and bend the vamp inwardly toward the medial line of the shoe.

60

8. A vamp trimming machine having, in combination, a vamp trimming knife arranged to trim the projecting edges of the vamp and lining of a lasted shoe, a guide to bear against the insole and determine the position of the shoe with relation to the knife and a vibrating vamp bending device carried by the knife and arranged to engage the vamp and press the vamp into the shoulder at the edge of the insole.

70

In testimony whereof I affix my signature, in presence of two witnesses.
